UNITED STATES PATENT OFFICE.

MARY J. CHESLEY, OF SPRINGFIELD, OHIO, ASSIGNOR OF ONE HALF TO
HENRY C. WILSON, OF SAME PLACE.

DESIGN FOR A KETTLE-CLEANER.

SPECIFICATION forming part of Design No. 24,772, dated October 22, 1895.

Application filed August 9, 1895. Serial No. 558,794. Term of patent 7 years.

To all whom it may concern:

Be it known that I, MARY J. CHESLEY, a citizen of the United States, residing at Springfield, county of Clark, State of Ohio, have invented and produced a new Design for Kettle-Cleaners, of which the following is a specification, reference being had to the accompanying drawing, which is a complete illustration thereof.

The drawing represents a complete view of the kettle-cleaner, showing my design.

The design consists of a cylinder *a*, provided with a triangular flange *b*, as shown.

What I claim is—

The design for a kettle cleaner as herein shown and described.

MARY J. CHESLEY.
